HOUSEHOLD OIL BURNER

Almeda Page, Bristol, Conn., assignor to Triple-Seal, Incorporated, Plainville, Conn., a corporation of Connecticut

Application August 23, 1932. Serial No. 630,012

8 Claims. (Cl. 158—87)

This invention relates to burners which use liquid fuel and are designed to be placed in stoves, ranges and heaters, and particularly to the mounting of such burners.

5 The object of the invention is to so construct and mount the burners that they may be arranged in a stove, range, or heater, in such manner as to ensure the greatest efficiency for the desired use.

10 In attaining this object pluralities of burners are so mounted that they may be positioned in various relations to each other and at different heights in order that they may conform to the especial conditions met in the particular places 15 in which they are to be used, that is, the burners may be variously combined and separated or brought close together, depending upon the shape of fire box or location of the water heater or oven of the stove, range or heater in which they are to 20 be set.

Fig. 1 of the accompanying drawing shows a plan view of a form of the apparatus which has two sets of three burners each arranged in one relation to each other, the cover plate of one of 25 the sets being omitted.

Fig. 2 shows a side elevation of the same with one of the burner sets cut in central vertical section.

Fig. 3 on smaller scale shows a plan view of a 30 three unit burner.

Fig. 4 is a detail showing the connection between a burner vaporizing cup and the supporting bar.

Fig. 5 is a diagrammatic view illustrating an 35 extended relation to which the burners may be adjusted.

Fig. 6 is a similar view illustrating a contracted arrangement of the burners.

The apparatus shown has a tubular post 1 that 40 may be fastened vertically in a stove, range or heater, by any suitable means. Fitted on the post is a supporting bar 2. This bar is capable of being raised and lowered and also rotated on the post, and it is fastened in the position to 45 which it is adjusted by a screw 3.

The structure depicted has two disks 4 with integral arms 5 that are fastened to the ends of the supporting bar by bolts 6. The upper faces of these disks are recessed to form vaporizing 50 chambers 7, and passages 8 lead from these chambers to central intake openings 9.

The structure illustrated has two burner bases 10 each having a central circular section 11 the under side of which is shaped to set on a packing 55 12 in the vaporizing chamber. Integral with

the central section of each base are three skeleton sections 13 that in their upper faces have annular wick grooves 14 containing wicks 15 fabricated of any suitable material, for example, asbestos. Arc-shaped ports 16 are made through 60 the central portion of the base from the vaporizing chambers to the wick grooves.

Mounted on the walls of the wick grooves are the usual concentrically arranged perforated cylindrical shells 17. On top of the shells is a 65 cover 18 which may be made in a single piece for each unit or of several pieces, as desired. Perforations 19 are made in the cover over the spaces between the shells to permit the escape of the products of combustion and thus allow the necessary draft for supporting combustion. The edges of the cover plates are preferably provided with flanges 20 and portions in from the edges may be depressed in such manner as to retain the upper edges of the shells correctly spaced. 70 The cover plates may be fastened in place by bolts 21 which pass through the plates and the bases. The burner units are shown as secured to the vaporizer disks by means of a threaded stud 22 and pin 23.

When the pins 23 are loosened the burner units 75 may be rotated to various positions, and upon loosening the screw 3 and bolts 6 the supporting bar may be turned so as to swing the units toward or from each other. After the units have 80 been adjusted to the required relations and raised or lowered to the desired level, the screws and bolts are tightened so as to hold the assembly rigid. Fig. 5 diagrammatically indicates the supporting bar turned so as to give the units a 85 wide spread, and Fig. 6 indicates the supporting bar turned so as to draw the units compactly together. The number of burners and the number 90 of units may be varied as may be the number of wick grooves and shells, without departing from 95 the invention.

After the units have been adjusted so that they 100 will be located in the most efficient position in the fire box of the stove, range or heater in which they are to be placed, intake pipes 24 are connected with the intake openings in the under side of the vaporizing disks. At the lower ends of these intake pipes there are shown fittings 25 with plugs 26 that may be removed for cleaning the pipes. Connected with the fittings by suitable couplings are fuel supply pipes 27 that lead 105 from any suitable reservoir of fuel.

The elements are cheap to manufacture, and they may be assembled in many relations. As a result of the provision for raising and lowering 110

the burners, swinging them and rotating them to various positions, the apparatus may be arranged in stoves, ranges or heaters of various shapes and sizes in such manner as to obtain the maximum effect of the flame, that is, the burners may be spread apart, they may be nested, or they may be turned to one side or the other in order that they be closely associated with a water container or an oven. The fuel passes freely into the vaporizing disks from the vertical pipes and in the chambers is quickly vaporized. Any desired means may be arranged for igniting the fuel.

The invention claimed is:

1. An oil burner comprising supporting means, a member adjustable on said supporting means, a plurality of vaporizing chambers adjustably attached to said adjustable member, oil supply means communicating with each vaporizing chamber, a burner base mounted on each vaporizing chamber and closing the open top thereof, each burner base having a plurality of annular wick grooves the centers of which are equi-distant from the axis of the base in which they are contained, ports extending from said grooves to the vaporizing chamber below, a plurality of pairs of concentric perforated shells on each base each pair being mounted above and communicating with one of said annular grooves, and cover plates at the top of said shells.

2. An oil burner comprising supporting means, a member adjustable on said supporting means, a plurality of vaporizing chambers adjustably attached to said adjustable member, oil supply means communicating with each vaporizing chamber, a burner base rotatably mounted on each vaporizing chamber and closing the open top thereof, each burner base having a plurality of annular wick grooves the centers of which are equi-distant from the axis of the base in which they are contained, ports that provide communication in all positions of the base, extending from said grooves to the vaporizing chamber below, a plurality of pairs of concentric perforated shells on each base each pair being mounted above and communicating with one of said annular grooves, and cover plates at the top of said shells.

3. An oil burner comprising supporting means, a bar horizontally and vertically adjustable on said supporting means, a plurality of horizontally adjustable vaporizing chambers mounted on said bar, oil supply means communicating with each vaporizing chamber, a burner base mounted on and rotatably adjustable with relation to each vaporizing chamber and closing the open top thereof, each burner base having a plurality of annular wick grooves the centers of which are equi-distant from the axis of the base in which they are contained, ports extending from said grooves to the vaporizing chamber below, a plurality of pairs of concentric perforated shells on each base each pair being mounted above and communicating with one of said annular grooves, and cover plates at the top of said shells.

4. An oil burner comprising supporting means, a member adjustable on said supporting means, a plurality of vaporizing chambers attached to said adjustable member and horizontally adjustable with relation thereto, oil supply means communicating with each vaporizing chamber, a burner base mounted on and rotatably adjustable with relation to each vaporizing chamber and closing the open top thereof, each burner base

having a plurality of annular wick grooves the centers of which are equi-distant from the axis of the base in which they are contained, ports extending from said grooves to the vaporizing chamber below, a plurality of pairs of concentric perforated shells on each base each pair being mounted above and communicating with one of said annular grooves, and cover plates at the top of said shells.

5. An oil burner comprising supporting means, a plurality of horizontally adjustable vaporizing chambers mounted on said supporting means, oil supply means communicating with each vaporizing chamber, a burner base rotatably mounted on each vaporizing chamber and closing the open top thereof, each burner base having a plurality of annular wick grooves the centers of which are equi-distant from the axis of the base in which they are contained, ports extending from said grooves to the vaporizing chamber below, and a plurality of pairs of concentric perforated shells on each base each pair being mounted above and communicating with one of said annular grooves.

6. An oil burner comprising supporting means, a member adjustable on said supporting means, a plurality of vaporizing chambers adjustably attached to said adjustable member, oil supply means communicating with each vaporizing chamber, a burner base rotatably mounted on each vaporizing chamber and closing the open top thereof, each burner base having a plurality of independent annular wick grooves the centers of which are equi-distant from each other, said grooves overlapping the vapor chamber below, ports that provide communication in all positions of the base, extending from said grooves to the vaporizing chamber below, a plurality of pairs of concentric perforated shell on each base each pair being mounted above and communicating with one of said annular grooves, and cover plates at the top of said shells.

7. An oil burner comprising supporting means, a member adjustable on said supporting means, a vaporizing chamber attached to said adjustable member and horizontally adjustable with relation thereto, oil supply means communicating with said vaporizing chamber, a burner base mounted on and rotatably adjustable with relation to said vaporizing chamber and closing the open top thereof, said burner base having a plurality of annular wick grooves the centers of which are equi-distant from each other and from the axis of the base, ports extending from said grooves to the vaporizing chamber below, and a plurality of pairs of concentric perforated shells on each base each pair being mounted above and communicating with one of said annular grooves.

8. An oil burner comprising supporting means, a member adjustable on said supporting means, a vaporizing chamber adjustably attached to said adjustable member, oil supply means communicating with said vaporizing chamber, a burner base mounted on said vaporizing chamber and closing the open top thereof, said burner base having a plurality of annular wick grooves which overlap the vaporizing chamber, ports extending from the overlapping sections of said grooves to the vaporizing chamber below, and a plurality of pairs of concentric perforated shells on said base each pair being mounted above and communicating with one of said annular grooves.
